UNITED STATES PATENT OFFICE.

ROBERT I. BENTLEY, JR., OF SAN JOSE, CALIFORNIA, ASSIGNOR TO MUIRSON LABEL COMPANY, OF SAN JOSE, CALIFORNIA, A CORPORATION OF CALIFORNIA.

DISPLAY-PACKAGE.

1,203,963.

Specification of Letters Patent.

Patented Nov. 7, 1916.

Application filed November 23, 1915. Serial No. 62,972.

To all whom it may concern:

Be it known that I, ROBERT I. BENTLEY, Jr., a citizen of the United States, residing at San Jose, in the county of Santa Clara and State of California, have invented certain new and useful Improvements in Display-Packages, of which the following is a specification.

My invention relates, in general, to the art of displaying goods, and, in particular, to the practices, methods and means employed in the exhibition of comestibles, especially fruit in boxes or packages.

In this art two considerations may be regarded as fundamental, namely those of sanitation and attractiveness. These, in some sense are antagonistic, in that the former depends in great part upon closure and the latter upon exposure. To harmonize these and make it possible at the same time to protect the goods and to agreeably display them is the object of my invention.

To make this clearer the specific example of a box of dried prunes may be taken. In packing prunes in a box it is the custom to place a layer of the fruit in orderly arrangement in the bottom of the box, fine specimens being selected for the composition of this layer. The remainder of the box is then filled without regard to order or selection. Then the cover is nailed on. When this box reaches the retailer, he inverts it by making that which was the bottom the top, and he then removes this new top, thereby exposing the orderly arranged layer. The box is then set up to view at an angle, usually endwise.

It is a well recognized psychological fact that there is special attraction in numbers, and that when there is a multitude from which to select, an incentive to purchase is presented which is wholly apart from and is in addition to the general desirable appearance and orderly arrangement of the goods. This complete effect, however, can only be preserved, in the example under consideration, by keeping the box full and not disturbing the attractive orderly arranged display layer; but obviously, this is inconsistent with selling from the box, and, moreover, is not sanitary for the fruit should be disposed of within a reasonable time after exposure. The expedient of using a glass pane to cover the fruit does not fully serve the end in view, for while it serves to cover

the contents of the box, it does not prevent that loss of attractiveness which must immediately follow the disturbance of the orderly arranged layer, or, if it be conceived, as might be the case with some fruit, that some regard for order may exist throughout the mass, the glass pane does not maintain the appearance of fullness nor conceal the gradual waste of contents due to sale therefrom.

My invention contemplates the provision of means for covering the fruit while permitting ready access to it, said means being of such a nature as to present at all times the appearance of fullness and orderly arrangement regardless of the real condition, thereby providing a display package fulfilling all the requirements of sanitation and attractiveness.

In the accompanying drawings, to which reference is hereby made, I illustrate the best form in which my invention may be embodied.

In these drawings—Figure 1 is a view of my display package showing it in its normal condition of display, the ordinary box cover having been removed and set to one side, as shown. Fig. 2 is a cross section of the box showing more particularly one form of the readily detachable connections which maintain the relation of display cover to the box, and showing also, from the volume of fruit in the box, that it has been drawn upon for sale. Fig. 3 is a detail view showing another form of detachable connection for the display cover.

1 is a box, of which 2, shown in Fig. 1 as removed, is the ordinary cover.

3 is the display cover. This is a plate of any suitable material. In practice, it will be of card-board or stiff paper. It is of a size to fit within the box and cover its contents. One essential feature of this cover is that it bears upon its outer face, as is shown in Fig. 1, the pictorial representation of an orderly arranged layer of the box contents. The photographic and lithographic arts now make it possible to provide a realistic and attractive picture of this subject. Another essential of this cover is that it must maintain a fixed relation or position in the box without regard to the volume of the box contents. This position is at the top of the box, so that whatever may be the level of the fruit in

the box, the display cover will, by its position, convey at all times the impression of fullness. Moreover the connections or supports by which this position is maintained 5 must be of some readily detachable character in order to permit the ready removal of the display cover in order to get at the contents for sale, and to replace said cover. Many forms of connection or support may 10 be employed. For example, I show in Figs. 1 and 2 tongues 4 on the display cover, adapted to fit in grooves 5 in the box, and in Fig. 3, I show ledges 6 on the box upon which the display cover may rest. I am 15 not to be confined to these forms of connection or support, however, for many others may be found practicable.

The main point is that the display cover is fixed in position in the top of the box 20 and is not dependent for its support upon the fruit itself which would, as its volume decreases, cause the cover to follow down and thus destroy the appearance or impression of fullness.

25 In practice, it is contemplated that the packer will place the fruit in the box without regard to special orderly display arrangement other than may be dictated by economy of space or general principles of 30 packing. When the box is full he will insert in its place the pictorial display cover 3. Then he will nail the ordinary cover 2 upon the box. When the box reaches the retailer, he will remove and set aside the 35 ordinary cover 2, and will set the box up for observation with its display cover in full view. This cover will indicate to the purchaser the nature of the contents of the box. It will satisfy him of the protection 40 of said contents from contamination. And, finally, it will attract him both from its appearance of fullness and by reason of its showing of orderly arrangement. These

are the objects of successful display. He may be served from the contents of the 45 box by removing the display cover, and when said cover is replaced the normal desired condition is restored.

I am aware of the practice of placing in boxes, containers and other packages, what 50 is termed in the art a "collar." This is usually a picture card or sheet having only an ornamental value and not indicative of the contents of the box. It is intended to be and is usually removed when the box is 55 opened, or if it be allowed to remain, it continues to serve only its original purpose of ornamentation.

I am also aware of the practice of pasting 60 around the exterior of a can a label highly glazed and printed to represent a transparent jar filled with fruit indicative of the contents of the can, and I also know of the practice of pasting on the exterior of a container a lithographic label pictorially indicating 65 its contents. I do not claim these as my invention, but

What I do claim as new and desire to secure by Letters Patent is—

A display-package comprising a container 70 having a cover; an opaque display-cover having on its face a pictorial representation of an orderly arranged layer of the contents of the container; and means for removably supporting said display cover in 75 a fixed plane within the top of said container under its cover and directly above and completely covering its contents.

In testimony whereof I have signed my name to this specification in the presence 80 of two subscribing witnesses.
